E. C. WILSON.

UNDERREAMER.

APPLICATION FILED MAR. 18, 1913.

Patented May 16, 1916.

1,183,151.

UNITED STATES PATENT OFFICE.

ELIHU C. WILSON, OF LOS ANGELES, CALIFORNIA, ASSIGNOR TO WILLIAM W. WILSON,
OF LOS ANGELES, CALIFORNIA.

UNDERREAMER.

1,183,151.

Specification of Letters Patent. Patented May 16, 1916.

Application filed March 18, 1913. Serial No. 755,170.

To all whom it may concern:

Be it known that I, ELIHU C. WILSON, a citizen of the United States, residing at Los Angeles, in the county of Los Angeles and 5 State of California, have invented new and useful Improvements in Underreamers, of which the following is a specification.

This invention relates to underreamers, such as are employed in enlarging oil well 10 and other well holes to permit the lowering of the casing in the hole following the drilling operation; and the invention constitutes an improvement upon or departure from the invention disclosed in and patented by 15 Letters Patent of the United States issued to me July 31, 1906, for underreamers, Number 827,595.

The present invention relates particularly to the means for holding one end of 20 the spring which is employed in expanding the cutters or bits of the reamer into working position. It has been found in practice that the means disclosed in said Letters Patent Number 827,595, while operative and 25 performing the functions required of them, are, under certain conditions, open to certain objections which are overcome by the use and substitution therefor of the means set forth and embodying the present invention.

The present invention has for particular objects the provision of an improved underreamer, and particularly of improved means of the general nature specified as a feature 35 of underreamers, which will be superior in point of simplicity and inexpensiveness of construction, facility in assembling and disconnection of parts and features, durability or length of life, freedom from liability to 40 get out of order in long continued service, and positiveness in operation, and which will be generally superior in efficiency and serviceability.

With the above and other objects in view 45 the invention consists in the novel and useful provision, formation, construction, combination, association and relative arrangement of parts, members and features, all as hereinafter described, shown in the drawing 50 and finally pointed out in claims.

In the drawing: Figure 1 is a fragmentary vertical sectional view of a portion of a joint of casing such as is employed in well holes with the shoe thereof, and further of 55 the principal features of construction of an

improved underreamer constructed and organized in accordance with the invention, the cutters or bits being in contracted positions; Fig. 2 is a similar view showing the cutters in expanded positions; Fig. 3 is a 60 fragmentary view of the underreamer with the cutters or bits removed, the view being taken in a line of vision at right angles to that of Figs. 1 and 2; and Fig. 4 is a detail transverse sectional view taken upon the 65 line x^4-x^4 , Fig. 1, and looking in the direction of the appended arrows.

Corresponding parts in all the figures are designated by the same reference characters.

Referring with particularity to the drawing, 5 designates the hollow body and A and B the cutters or bits of an underreamer constructed to embody the invention in one form. The underreamer is shown as within the casing 6 and the shoe 7 in Fig. 1, and as projected at its lower end beneath the shoe in Fig. 2, the cutters being held collapsed in Fig. 1, by the shoe and casing, and being in expanded positions in Fig. 2, such expansion being caused 70 by a coil spring 8 within the hollow body 5 and surrounding a rod or mandrel 9, which plays vertically in the hollow body, the spring being confined between a nut or removable stop 10 at the upper end of the 75 spring actuated rod or mandrel 9, and a key 11 detachably accommodated within a transverse slot 12 in the rod 9 adjacent to the lower end thereof. The slot 12 is elongated longitudinally of the rod, so that the key 90 may remain in relatively fixed position during the longitudinal movement of the rod. A transverse slot 13 in the hollow body 5 permits the insertion and withdrawal of the key. The key 11 is provided with tapered 95 end portions 11^a, and with a bottom extension or head 11^b which fits within the bore of the hollow body 5, being held therein by the tension of the spring 8, and effectually preventing the key from displacement. The 100 transverse slot 13 in the body is of a width, as is the slot 12, properly to snugly accommodate the key 11; and the slot 13 is of sufficient height, lengthwise of the body 5, to permit the key with its head 11^b to be inserted and withdrawn, from the slots 12 and 105 13, in accommodation of the extension or head 11^b. Wedges are employed for both inserting and prying out the key 11, under the pressure of the spring 8, such wedges 110

being inserted between the tapering end or ends 11^a of the key 11. The lower end of the rod 9 has a T-head 9^a entering recesses 14 in the inner faces of the cutters A and B, and permitting the cutters to swing upon the T-head in the collapsing and expanding movements. Above the T-head 9^a the rod 9 has bearing surfaces 9^b for the inner faces of the cutters or bits, preventing lateral displacement of the bits. The lower end of the body 5 is bifurcated to form spaced prongs 5^a and 5^b, separated by an open space, within which the T-head 9^a plays, and said prongs have at each edge terminal portions 15 provided with synclinal expansion faces 5^c, producing a violent wedge action upon the cutters, and upper slightly outwardly inclined expansion and thrust-bearing faces 5^d producing final and relatively slight expansion action of the cutters, the cutters being provided with lateral extensions forming shoulders b which extensions and shoulders co-act with these expansion faces 5^c and 5^d, when the cutters are raised by the spring 20 8 to expand the cutters, and riding over such expansion surfaces when the cutters are drawn down into collapsed positions. These shoulders b also impart some of the thrust of the cutters to the prongs in underreaming, the remaining portion of the thrust being imparted to thrust bearings c at that portion of the hollow body 5 at which the formation of the prongs 5^a and 5^b commences. Dove-tails 15 are formed at the 25 sides and inner edges of the prongs 5^a and 5^b, co-acting with dove-tails 16 upon the sides of the cutters. These dove-tails are so arranged as to allow play to the shank 17 in the collapsing and expanding actions of 30 the cutters. It will be understood that T-head 9 lies across the space between the prongs 5^a and 5^b, in a plane intermediate of and parallel with the planes of the prongs. A retaining bolt 18 spans the space 35 between the prongs adjacent to the lower ends thereof serving to limit the downward movement of the T-head 9^a and also to prevent the cutters from falling out beneath the prongs should the spring actuated rod 50 9 or T-head 9^a become broken.

The parts are assembled from the lower end of the body 5, by first inserting the spring actuated rod 9 with its spring, then hanging the cutters upon the T-head 9^a and 55 moving them with the rod 9 upwardly, whereupon the key 11 is wedged through the slot 13 into the slot 12, and the head 11^a is seated in the bore of the hollow body 5 which it closely fits. When it is desired to 60 disconnect the parts of the underreamer, a suitable wedge is applied to one or both of the tapered ends 11^a of the key 11, raising it up to free the head 11^a, whereupon the key may be driven out laterally from the 65 slots 12 and 13.

The operation and method of use of the improved underreamer will be readily understood by those skilled in the art from the above description of construction and method of use and operation.

Having thus described my invention, I claim and desire to secure by Letters Patent:

1. An underreamer having a hollow body and a slotted rod mounted to reciprocate in the same and provided with a spring surrounding the rod and acting at one end to cause movement of the rod, such rod being adapted to support and actuate cutters, and the hollow body being provided with a transverse slot; the combination with such rod and spring and cutters and body; of a single-piece device adapted to be seated at its ends in the openings in the body provided by the transverse slot and to traverse the slot in the rod and to constitute a stop for one end of said spring, and means for preventing endwise movement of said single-piece device in both directions when so inserted.

2. An underreamer, comprising a hollow body, a rod movable within the hollow body, cutters connected with the rod to move with the same, means for causing the expansion of the cutters in the movement of the rod, a spring acting upon the rod to move it in one direction, and means confining the spring at one end and consisting of a key engaged with the hollow body and accommodated in a slot in the rod; said key having an extension seated in the bore of the hollow body and held therein under the tension of the spring.

3. An underreamer comprising a body having a central bore, a rod mounted in said bore, said body and rod provided with registering slots, a key or gib loosely mounted in said slots and having means at the bottom for anchoring in said body, a spring surrounding said rod and connected thereto at the top thereof, and operatively connected to said key at its lower end, said rod provided with bit engaging means.

4. An underreamer comprising a body having a central bore, a rod or mandrel mounted in said bore, said body and rod provided with registering slots, a key or gib mounted in said slots and having a projection or wing fitting within the bore of said mandrel below said slots and shouldering against the wall upon transverse movement in either direction, a spring mounted on said gib and operatively connected with said rod, said rod provided at its lower end with bit engaging and supporting means, said rod being enlarged at its lower end and provided with surfaces adapted to support the inner ends of the bits or cutters, and bits or cutters mounted on said rod.

5. An underreamer comprising a body having a central bore, a rod mounted to reciprocate in said bore, said body and rod pro-

- vided with slots, a key mounted in said slots, said key having a projection or wing projecting downward from the slot of the body into the central bore and preventing lateral motion of the key, a spring mounted on said key and coiled about said rod, means at the upper end of said rod adjustably connecting said rod and spring, means at the lower end of said rod for engaging and supporting the bits or cutters, and cutters or bits.
6. An underreamer comprising a body having a central bore, a rod or mandrel mounted in said bore, said body provided with a slot, said rod provided with a longitudinal slot, a key or gib mounted in said slot and provided with a downwardly projecting portion adapted to contact with the wall of the central bore below said slot and prevent lateral displacement of the key from either side of the slot, a spring mounted on said gib and operatively connected with said rod, said rod provided at its lower end with a bit engaging head or key.
7. An underreamer comprising a body having a central bore, a spring actuated rod mounted in said bore, said rod provided with bit carrying means, and a key loosely mounted in said body and held therein by the tension of said spring.
8. An underreamer comprising a hollow body, a spring actuated rod mounted therein and provided with bit carrying means, and a key loosely mounted in said body and operatively connecting said rod and body.
9. An underreamer comprising a hollow body, a reciprocating rod, a spring and a key operatively mounting said rod in said body, said key fitting loosely in said body and held therein by spring tension on the top, and means preventing the key sliding laterally in the body without overcoming the downward pressure of the spring on the key.
10. An underreamer comprising a body having a central bore, a rod or mandrel mounted in said bore, said body and rod provided with registering slots, a key or gib mounted in said slots, the slot in the rod being of sufficient longitudinal extension to permit the movement of said rod longitudinally of said body, a key or gib loosely mounted in said slots and having a projection or wing projecting downward into the central bore below the walls of the slot in the body and anchoring said key or gib against movement transversely of said body, a spring mounted on said gib and operatively connected with said rod, said rod provided at its lower end with bit engaging means, bits tiltingly carried thereby, and bearings for the inner faces of said bits formed on said rod and adapted to prevent lateral displacement of said bits.

In testimony whereof, I have signed my name to this specification in the presence of two subscribing witnesses.

ELIHU C. WILSON.
